UNITED STATES PATENT OFFICE.

ORLAND D. ORVIS, OF NEW YORK, N. Y., ASSIGNOR TO ORVIS ECONOMY FURNACE CO., OF NEW YORK, N. Y., A CORPORATION OF NEW YORK.

STEAM-BOILER FURNACE.

No. 927,672.

Specification of Letters Patent.

Patented July 13, 1909.

Application filed April 16, 1907. Serial No. 368,564.

To all whom it may concern:

Be it known that I, ORLAND D. ORVIS, a citizen of the United States, residing in the city of New York, borough of Manhattan, 5 and State of New York, have invented a certain new and useful Steam-Boiler Furnace, of which the following is a specification.

This invention is a steam boiler furnace, and it appertains more especially to that type 10 of water tube boilers wherein inclined water tubes are employed in connection with means operating to direct the smoke, gases and other products of combustion in a circuitous path back and forth between and around the 15 aforesaid inclined water tubes.

In one type of furnace constructed in accordance with this invention, a plurality of mantles or arches lie over the grate and within the grate-chamber, said arches being 20 spaced relatively to one another to produce an intermediate throat for the passage of the products of combustion, and means whereby a blast, or a plurality of blasts, of steam and air, either singly or jointly, are projected 25 across the aforesaid throat, whereby said blast or blasts are thrown into the ascending current of the products of combustion for the purpose of disintegrating the smoke, increasing the combustion of the gases, and augment- 30 ing the draft and the heat.

It is preferred to employ blast devices operating to direct currents in intersecting paths and across the aforesaid throat, and, further, to combine steam and air prior to 35 discharging the blast or blasts into the products of combustion. Furthermore, it is preferred to provide means for securing a circulation of water from the boiler through the grate-chamber, for the two-fold purpose 40 of generating steam and for reducing the temperature of certain metal parts employed in the grate chamber for supporting the mantles or arches therein.

In the accompanying drawings, I have 45 illustrated one practical embodiment of the invention, but the construction shown therein is to be understood as illustrative only, and not as defining the limits of the invention.

Figure 1 is a vertical section showing the 50 present invention in connection with a water tube boiler of that type wherein water tubes are employed in an inclined position relative to the grate-chamber and the escape flue or flues. Fig. 2 is an enlarged vertical section 55 through the grate-chamber of the water tube

boiler shown in Fig. 1, the dotted lines illustrating the direction of the blasts from a plurality of blast pipes, the plane of the section being indicated by the dotted line 2—2 of Fig. 3. Fig. 3 is a horizontal section 60 taken in the irregular plane indicated by dotted line 3—3 of Fig. 2. Fig. 4 is a vertical cross section on the line 4—4 of Fig. 2.

The water tube boiler shown in Figs. 1 to 4 inclusive, consists of a grate-chamber, A, the 65 inclined water tubes, B, and the steam dome, C. In the chamber, A, is a grate, a, supported at one end by a bridge wall, D. Extending upwardly from this bridge wall is a partition, E, which directs the products of 70 combustion upwardly through one portion of the water tubes, B, over the grate-chamber. Extending downwardly from the boiler, C, is a baffle, F, and from this baffle extends another partition, E', whereby the products of 75 combustion are caused to pass downwardly between the partitions, E E', and thence upwardly in rear of the partitions, E', to the outlet, e, which communicates with a stack or up take. 80

The generator thus far described is of the familiar type known in the art as a water tube boiler, and the several parts may be constructed and arranged in any usual or preferred way. 85

Within the grate-chamber, A, at a suitable height above the grate, a, therein, are mantles or arches, G, G'. Said mantles or arches are supported partly by water circulating pipes, H, H', and by brick work, I, I', in 90 which brick work there are embedded the blast pipes, J, J'. 95

The mantle, G, is supported at its front end on the wall, a', of the boiler setting, while the inner end of said mantle is shown as resting upon the blast pipe, J, and the brick work, I. The other mantle, G', is supported at its rear edge on the bridge wall, D, while the front edge of said member rests on the blast pipe, J', so as to be supported by the 100 brick work, I'. The two mantles, G, G', are spaced at their adjacent edges so as to produce a throat, K, between them, through which throat the smoke, gases and other products of combustion are adapted to pass 105 in order to escape from the grate-chamber, A, into the circulating flues around the inclined water tubes, B. It is preferred to arrange the mantles in approximately horizontal positions and so that they extend 110

from side to side of the furnace. Each mantle may be composed of any suitable or appropriate material and installed within the grate-chamber in a suitable way, but in one practical form of the invention each mantle is composed of blocks or slabs of fire proof material, such as fire clay, said blocks being molded in a suitable shape and size, and baked or otherwise treated in a way to render it indestructible to the action of heat.

I may employ a single water circulating pipe in connection with each brick work, I, I', but as shown in Figs. 1 and 2, it is preferred to employ said pipes, H, H', in pairs. Said pipes, H, H', extend horizontally across the grate-chamber so that the end portions of the pipes are embedded in the side walls, a², of the furnace, see Fig. 4. The end portions of the pipes, H, H', as well as the end portions of the pipes, H', H', are coupled or united by headers, h, h', which are, also, embedded in the side walls, each header being provided with a suitable removable closure, h². The two pairs of pipes, H, H', are spaced at the respective sides of the throat, K, and as said pipes are supported directly by the side walls of the furnace, they furnish a convenient and secure means for supporting the brick work, I, I'. It is evident that the brick work should be composed of fire proof material, and that said brick work may be easily, quickly and accurately laid on the pairs of water circulating pipes, H, H'. During the installation of the brick work, the blast pipes, J, J', are placed in position so as to be embedded in the brick work, or incased thereby. The tiles composing the mantles or arches, G, G', are adapted to be laid or placed in position easily, quickly and accurately, and the entire apparatus may be installed without the employment of skilled labor.

The water pipes, H, H', may be connected in any suitable or approved manner with the inclined water tubes, B, or with other parts of the water tube boiler. In Figs. 3 and 4 I have shown circulating pipes, L, L', connected to the respective headers, h, h', of the pipes, H, H', and these circulating pipes, L, L', are adapted to be connected with the inclined water tubes, or with any other part of the boiler, for the purpose of securing the desired circulation of water through the pipes, H, H', whereby said pipes are protected against the excessive heat of the furnace.

It is preferred to employ two blast pipes, J, J', and to provide said pipes with series of nozzles, j, j', respectively, as shown in Figs. 2 and 3. The rear side of the brick work, I, or that side next to the throat, K, is provided with a series of openings, i, which are inclined upwardly, and into these openings extend the nozzles, j, of the blast pipe, J, whereby the nozzles are adapted to direct a

blast rearwardly and across the throat, K, said blast being in upwardly inclined paths. The front surface of the brick work, I', or that surface next to the throat, K, is provided with a series of openings, i', into which extend the nozzles, j', of the blast pipe, J', and these nozzles are inclined slightly in an upward and forward direction for the purpose of directing a blast across the throat, K, the direction of the blast from the nozzles of the pipe, J', being opposite to the blast from the nozzles of the pipe, J. From this description it will be apparent that the two blast pipes, J, J', are provided with nozzles arranged to direct blasts in opposite directions one to the other, said blasts from the pipes intersecting one with the other. Furthermore, the nozzles, j, of the pipe, J, are not in the same plane longitudinally of the furnace chamber as the nozzle, j', of the other blast pipe, J', but as will be noted by reference to Fig. 3, the nozzles of one blast pipe are in alternate relation to, or out of alinement with, the nozzles of the other blast pipe, whereby the nozzles of the two blast pipes are staggered. Furthermore, it is preferred to employ nozzles which are of flattened construction, in order that the blast issuing from the flattened or elongated nozzles may spread or diverge horizontally. The nozzles of the two blast pipes employed in my invention are arranged to direct the jets or streams of steam and air in such a way across the throat, K, as to break up or disintegrate the cloud of smoke which arises from the bed of fuel resting on the grate, a, and the result of this injection of the blast is to intimately combine steam and air with the products of combustion for the purpose of increasing the combustion of the smoke and gases, whereby the intensity of heat is augmented by the admixture of oxygen with the gases and the thorough combustion of said gases is assured.

By reference to Fig. 2 of the drawings, it will be observed that the water pipes, H, H', and the brick work, I, I', are in planes below the ends of the mantles, G, G', which are supported by the front wall, a', and the bridge wall, D, respectively, and furthermore, that the adjacent ends of the mantles, G, G', are below the other ends of said mantles, whereby the mantles may be said to converge downwardly toward each other. The employment of the mantles over the grate, and spaced to produce the throat for the escape of the products of combustion, is an important feature of my invention, and the employment of one or a plurality of blast pipes for directing a blast or blasts across said throat is another important feature. In the practical operation of the furnace, the smoke and gases arising from the bed of fuel on the grate circulate in upward direction and strike against the mantles, but the blasts

- across the throat draw the smoke and gases downwardly and beneath the water pipes, H, H', and thence upwardly through the throat, whereby the products of combustion are 5 "whipped" or caused to move with increased velocity around the inner edges of the mantles and the adjacent pipes, H, H'. The effect of the increased velocity of the products of combustion is to increase the draft 10 through the grate and the fuel thereon, and at the same time steam and air are supplied to the gases for increasing the combustion.
- Any suitable means may be resorted to for injecting steam into the blast pipe or pipes in 15 order to induce the inflow of air into the said pipes, the air and steam being commingled and heated prior to delivery thereof into the combustion chamber.
- Having thus fully described this invention, 20 what I claim as new and desire to secure by Letters Patent is:—
1. In a boiler furnace of the class described, a grate chamber, a plurality of downwardly converging mantles spaced in said chamber to produce a throat for passage therethrough of products of combustion, and means for injecting upwardly converging blasts of steam and air across the aforesaid throat.
  2. In a boiler furnace, a grate chamber, a plurality of mantles separate from the walls of said grate chamber and extending toward each other from opposite walls of said chamber, said mantles being disconnected at their 35 adjacent ends and forming an intermediate opening through which flow the products of combustion from said chamber, and blast devices arranged to project blasts on upwardly converging lines and across said intermediate space.
  3. In a boiler furnace, a grate chamber, two mantles extending respectively from opposite walls of said chamber, the lower surface of each mantle being curved or arched 45 lengthwise of said chamber and the said arched surfaces of the two mantles presenting imperforate baffle surfaces for the impingement of products of combustion, said mantles being substantially equal in area 50 and being, also, separated at their inner adjacent ends, whereby there is produced an intermediate throat for the escape of products of combustion, and blast devices increased in said mantles at the inner separated 55 ends thereof, said blast devices having means for directing blasts in upwardly converging paths and across said throat.
  4. In a boiler furnace, a grate chamber, a plurality of mantles each composed of a row 60 of tiles or sections which are curved lengthwise of the grate chamber, one of said mantles extending backwardly from the front wall of the grate chamber, and the other mantle extending forwardly from the back wall of the chamber, said mantles being 65 separated at their adjacent ends and producing an intervening opening 70 above a grate in said chamber, and blast devices at the adjacent ends of the respective mantles for injecting blasts across said throat between said mantles.
  5. In a boiler furnace of the class described, a grate chamber, a plurality of downwardly converging mantles spaced in said chamber to produce a throat for the passage between them of products of combustion, and a plurality of blast pipes for directing steam and air in upwardly converging paths across said throat.
  6. In a boiler furnace, a grate chamber, disconnected mantles extending toward each other and from opposite walls of said chamber, said mantles being separated at their adjacent ends, thereby forming an opening 85 through which flow the products of combustion, and horizontal blast pipes incased in said mantles, at the adjacent edges thereof, 90 for directing blasts across said space which intervenes said edges of the mantles.
  7. In a boiler furnace of the class described, a grate chamber, two mantles extending inwardly from opposite walls of said chamber and separated at their adjacent edges to produce a throat for the passage of products of combustion, said mantles presenting imperforate baffle surfaces of substantially equal area, and said surfaces being 100 curved lengthwise of the grate chamber, a blast pipe at the inner edge of each mantle, and nozzles projecting from said blast pipes, the nozzles of one pipe being staggered relatively to the nozzles of the other pipe, and 105 said nozzles arranged to inject steam and air on upwardly converging lines and across the aforesaid throat between the mantles.
  8. In a boiler furnace, a chamber, separate mantles extending toward each other from 110 opposite walls of said chamber, the adjacent edges of said mantles being separated and producing an intervening opening through which flow the products of combustion, and blast pipes positioned substantially at the 115 separated edges of the mantles, one of said pipes being adapted to direct a blast in an upward and forward direction, and the other pipe operating to direct a blast in an upward and rearward direction, whereby said blasts 120 are directed in intersecting paths and across the space intervening said mantles.
  9. In a boiler furnace, a chamber, two arched mantles within said chamber and separate from the walls thereof, one of said 125 mantles extending from the rear wall of the chamber, and the other mantel extending from the front wall of said chamber, said mantles being separated at their adjacent ends and producing an intervening opening 130

through which products of combustion are free to flow in an upward direction, and blast pipes on the respective mantles, one of said pipes having nozzles for directing a blast in 5 a forward direction and across said intervening space, and the other pipe having nozzles operating to direct a blast in a rearward direction and across said intervening space.

10. In a boiler furnace, a chamber, two arched and disconnected mantles within said chamber, one of said mantles extending forwardly from a rear wall of the chamber and the other extending rearwardly from the front wall of the chamber, said mantles being 15 spaced to produce an opening intervening their adjacent ends, whereby products of combustion may flow in an upward direction and substantially centrally of said chamber, blast pipes on the respective mantles, and 20 nozzles on the pipes, the nozzles of one pipe operating to direct a blast in a forward and upward direction, and the nozzles of the other pipe directing a blast in a rearward and upward direction.

25. 11. In a boiler furnace of the class described, a grate chamber, horizontal water circulating pipes extending transversely across said chamber, two disconnected mantles each supported at one edge by one of said 30 pipes, said mantles extending in opposite directions from said pipes and toward opposite walls of said chamber, and said mantles presenting imperforate baffle surfaces which are curved lengthwise of the grate chamber, and 35 blast pipes parallel to the aforesaid water pipes, said blast pipes being arranged to direct a blast from the respective mantles and across a throat between said mantles.

12. In a boiler furnace of the class described, a grate chamber, two groups of horizontal water circulating pipes extending across said chamber, suitable tiles on said pipes, two mantles spaced in said chamber to produce between their adjacent ends a throat 45 for the products of combustion, each mantle being composed of arched tiles which are supported at the inner ends by the aforesaid tiles on one of said groups of water pipes, and blast pipes parallel to the water pipes and 50 adapted to direct blasts of steam and air across said throat.

13. In a boiler furnace of the class described, a grate chamber, groups of horizontal water pipes extending across said chamber, brick-work on each group of said pipes, arched mantles supported partly by the brick-work and extending outwardly therefrom to opposite walls of said chamber, said mantles being separated at their adjacent ends and producing a throat for the 55 passage of the products of combustion, and blast pipes incased in the brick-work and the mantles, said pipes having nozzles for directing blasts across the throat between 60 said mantles.

14. In a boiler furnace of the class described, a grate-chamber, arched mantles over a grate in said chamber and producing an intermediate throat for the passage of products of combustion, said mantles converging downwardly toward each other and separated by the aforesaid throat, and blast pipes at the adjacent edges of the mantles and provided with nozzles for directing blasts across the aforesaid throat. 75

15. In a boiler furnace of the class described, a grate chamber, arched downwardly converging mantles separated at their adjacent edges and producing an intermediate throat for the passage of products of combustion, and blast pipes at the adjacent edges of said mantles and adapted to direct blasts of steam and air in upwardly converging paths and across the aforesaid throat. 80

16. In a boiler furnace of the class described, a grate chamber, a bridge-wall, two arched mantles extending respectively from the front of the grate chamber and from the bridge-wall, said mantles converging downwardly and being separated to produce a 90 throat between their adjacent edges and each mantle presenting an imperforate arched baffle surface to the products of combustion, and means for directing blasts of steam and air in upwardly converging paths and across 95 the aforesaid throat.

17. In a boiler furnace, a grate chamber, a plurality of horizontal water tubes extending across said grate chamber, a row of tiles spanning the space between the pipes and 100 supported directly thereby, a blast pipe resting on the aforesaid tiles and located in a vertical plane intermediate the aforesaid water tubes, and other tiles substantially incasing the blast pipe and supported by the 105 first named row of tiles and the water tubes, said blast pipe having nozzles arranged to discharge blasts externally to the tiles.

18. In a boiler furnace, a grate chamber, a group of water-circulating pipes therein, tiles 110 resting on said pipes, a blast pipe located in a plane between the water pipes of said group and resting on said tiles, and other tiles incasing said blast pipe and supported by the first named tiles and said group of pipes. 115

19. In a boiler furnace, a grate chamber, a group of water-circulating pipes therein, tiles spanning the space between said pipes, a blast pipe located in a plane between the 120 pipes of said group and resting on said tiles, and other tiles co-operating with the first named tiles in incasing the blast pipe, all of said tiles being supported by the group of water-circulating pipes, which pipes are directly exposed to the heat of the grate chamber. 125

20. In a boiler furnace, a grate chamber, a group of water-circulating pipes therein, tiles resting on said pipes, a blast pipe resting on the tiles, and other tiles resting at one end or 120

the aforesaid tiles and partially increasing the blast pipe, said last mentioned tiles extending beyond the group of pipes and presenting an imperforate baffle surface for the impingement of products of combustion.

21. In a boiler furnace, a grate chamber, a group of water-circulating pipes therein, tiles resting on said pipes, a blast pipe resting on the tiles, and other tiles resting at one end on the aforesaid tiles and partially incasing the blast pipe, said last mentioned tiles being arched or curved beyond the group of pipes and presenting imperforate baffle surfaces which are curved lengthwise of the grate chamber.

22. In a boiler furnace, a grate chamber, a plurality of mantles positioned in said chamber and arched with respect to the plane of a grate therein, said mantles forming an open-

ing through which the products of combustion are adapted to flow in an upward direction, and a plurality of blast devices operating to direct blasts in opposite directions to each other and across the opening between said mantles, said blasts being directed, also, on upwardly converging lines, whereby the products of combustion rising from below the mantles are drawn forcibly around the inner adjacent edges thereof and the flow of said products of combustion is accelerated through the opening between said mantles.

In testimony whereof I have signed my name to this specification in the presence of two subscribing witnesses.
